UNITED STATES PATENT OFFICE.

SIDNEY RICHMOND PARK, OF WIGAN, ENGLAND.

HANDLE FOR SPADES, SHOVELS, FORKS, AND LIKE IMPLEMENTS.

1,077,550.

Specification of Letters Patent.

Patented Nov. 4, 1913.

Application filed June 6, 1912. Serial No. 702,026.

To all whom it may concern:

Be it known that I, SIDNEY RICHMOND PARK, a subject of the King of England, residing at 15 Wiend, Wigan, in the county of Lancaster, England, have invented certain new and useful Improvements in or Relating to the Handles of Spades, Shovels, Forks, and like Implements, of which the following is a specification.

10 This invention relates to handles of the split D or eye type, as commonly used for spades, shovels, forks, and like implements. Generally, such handles are formed or constructed in the following manner:—An ordinary wooden stem is split or cut down the center for the length required, and it is prevented from further splitting at the inner extremity of the cut by means of a transverse rivet; the bifurcated end of the stem 15 is then steamed, and by means of suitable apparatus the respective limbs or members thereof are curved or bent to form the sides of the D or eye. The ends of said side limbs or members are spanned by a cross or transverse piece of wood shaped suitable for grasping by the hand, and mounted upon a rivet which also passes through both of said side limbs or members; thus the handle is completed.

20 My invention has for its main object to provide new or improved means whereby said cross or transverse handle piece is prevented from revolving upon the rivet by which it is carried; and consists essentially 25 in the employment—at one or at both sides of the handle—of a washer, plate, or disk of metal or other suitable material provided on each side or face with a plurality of pins or nail-like projections, and having a central aperture or perforation through which the rivet passes, said washer or the like being disposed between a side limb or member of the handle and an end of said transverse handle piece, so that on the tightening of 30 the rivet and the resultant closing or inward movement of the side limbs or members, said pins or nail like projections pierce the side member and transverse handle piece, respectively, with the result that said transverse handle piece is positively prevented from rotation. Moreover, the pins or nail-like projections which pierce said side members also tend to minimize the effect of the

splitting of the latter, should such occur, by holding together the parts divided by the split.

I will further describe my invention with the aid of the accompanying sheet of explanatory drawings, in which:—

Figure 1 is an elevation, partly in section, 60 of a D or eye type of handle, provided with my improvements. Fig. 2 is a side elevation, in part broken away.

In the drawing, *a* represents the wooden stem, and *b b* the respective limbs or members of the bifurcated extremity thereof; *c* indicates the transverse handle piece, and *d* the rivet upon which it is mounted. At each side of said handle (*i. e.* between an end of the transverse handle piece *c* and a side limb or member *b*) there is fitted a metal washer *e*, on each side or face of which pins, or nail-like projections *f* are formed. Said washer *e* is provided with an aperture or perforation *g*, through which rivet *d* 70 passes. For the purpose of housing said washer, a recess or cavity *h* is formed within an end of the transverse handle piece *c* which is thereby enabled to butt closely against a side member *b*. Alternatively, said cavity or 75 recess *h* may be formed within a side member *b*; or it may be omitted altogether, the washer *e* in which case is preferably of the same diameter as or of similar contour to the end of the transverse handle piece *c*. 85

Having now described my invention what I claim as new and desire to secure by Letters Patent is:—

1. An implement handle comprising a bifurcated stem having the furcations in 90 separated and spaced relation, a transverse handle piece interposed between the end portions of the furcations, a metal plate inset in each end face of the transverse handle, spurs struck up from the body of 95 the metal in opposite directions transversely to the plane thereof and embedded in the material of the cross piece and the furcations, and a rivet passing through the furcations and handle piece and headed at the 100 ends.

2. An implement handle comprising a bifurcated wooden stem, whose furcations are sprung outwardly and bent into substantially parallel spaced relation near the 105 outer ends thereof, a transverse piece dis-

posed between and gripped by the parallel portions having recesses in its end faces, a sheet metal plate of less diameter than the handle piece seated in each recess, spurs 5 struck up from the body of each plate and extended from each face thereof into the face of the contiguous handle and cross piece, and a rivet passing through the furca-

tions, the cross piece and the plates and clamping them together.

In testimony whereof I affix my signature in presence of two witnesses.

SIDNEY RICHMOND PARK.
